UNITED STATES PATENT OFFICE.

CHARLES E. HARRELL, OF MONTGOMERY CITY, MISSOURI.

MAIL CATCHING AND DELIVERING APPARATUS.

No. 918,673.

Specification of Letters Patent. Patented April 20, 1909.

Application filed August 14, 1908. Serial No. 448,568.

To all whom it may concern:

Be it known that I, CHARLES E. HARRELL, a citizen of the United States, residing at Montgomery City, in the county of Montgomery and State of Missouri, have invented 5 a new and useful Mail Catching and Delivering Apparatus, of which the following is a specification.

This invention relates to apparatus for 10 catching mail and for delivering it to and from cars in motion.

The object of the invention is to provide 15 simple means which can be readily attached to the mail car and which will operate to securely hold one or more mail pouches or sacks until the point of delivery is reached.

A further object is to provide means, 20 cooperating with a stationary tripping device, whereby the supported pouches will be positively delivered to a crane arranged beside the track.

A further object is to provide simple means whereby the pouch-carrying device upon the car is permitted to give or yield under the 25 impact to which it is subjected during the interchange of mail.

A further object is to provide mechanism 30 whereby the release of the pouches from the mechanism upon the car is prevented unless the pouches are in position to be positively engaged and supported by the crane.

A further object is to provide a crane which can be readily adjusted to different heights and which includes a tripping member and a 35 holding member, said holding member being so shaped and positioned as to hold a pouch-carrying ring in position to be positively engaged by the mechanism on the car.

With these and other objects in view, the 40 invention consists of certain novel details of construction and combinations of parts, which will be hereinafter more fully described and pointed out in the claims.

In the accompanying drawings the preferred form of the invention has been shown.

In said drawings:—Figure 1 is a perspective view of the complete apparatus. Fig. 2 is an enlarged transverse section through that portion of the mechanism carried by the car, a 50 portion of the tripping arm being shown in position prior to entering the pouch-ring carried by the mechanism. Fig. 3 is a rear elevation of the pouch-ring, tripping-plate, and the adjoining portion of the arm carried by the car. Fig. 4 is a plan view of the parts 55 shown in Fig. 3. Fig. 5 is a detail side elevation of the inner end of the catcher arm showing the manner of connecting the same with the body of the car.

Referring to the figures by characters of reference, "A" designates a small car and to one side of the door "a" thereof is hinged an arm 1, preferably in the form of an elongated flat strip designed to swing in to the door or to swing outwardly into position at right angles to the side of the car. This arm 1 has an eye 2 extending from one face thereof and designed to be detachably engaged by a hook 3 formed at one end of a rod 4. This rod is slidably mounted within a tubular member 5 60 connected by means of an eye 6 with an eye or staple 7 arranged upon the other side of the door. A spring 8 connects the adjoining portions of the rod 4 and tubular member 5 65 and is secured at its ends to collars 9 and 10 70 secured to the rod 4 and the member 5 respectively. It will be apparent therefore that when the rod 3 is pulled longitudinally from the member 5 the spring 8 will be compressed and when the rod 4 is released said 75 spring will operate to return it to normal position relative to the member 5.

Projecting from one face of the arm 1 and preferably close to the upper edge thereof is an ear 11 extending between spaced ears 12. 80 A pivot pin 13 extends transversely through the ears 11 and 12. The ears 12 extend from the margin of a tripping plate 14, which, as shown in the drawings, is preferably crescent-shaped. This tripping-plate has spaced 85 prongs 15 extending from one face thereof and said prongs are preferably slightly curved from end to end as shown in Fig. 2, and, when the plate 14 is in its normal or vertical position, the ends of these prongs are 90 removably seated within openings 16 formed in the arm 1 close to the lower edge thereof. These prongs are preferably detachably connected to the tripping-plate, each prong being provided with a screw-threaded stem 17 95 extending through the plate and engaged by a nut or other device for holding it in place. Springs 18 are preferably connected to the upper portion of the arm 1 and the free ends 100 of the springs extend over the arm 1 and bear upon the upper portions of the ears 12. These ears are preferably formed with flat faces disposed at angles to each other so that

the springs will coöperate therewith to hold the plate 14 either in vertical or horizontal position. When the plate is swung out of vertical position but not far enough to assume a horizontal position, these springs will operate to return the plate to its vertical position. The springs also, obviously, prevent the plate 14 from swinging back and forth relative to the arm 1.

10 A plate 19 is secured to that face of the arm 1 opposite the ear 11 and extending upwardly from the lower portion of this plate is an arm 20. This arm 20 has an elongated forwardly extending finger 21, the free end of 15 which is curved upwardly as indicated at 22 so as to constitute retaining means as herein-after set forth.

The crane used in connection with the apparatus herein described preferably consists 20 of a tubular standard 23 having braces 24 extending to the upper end thereof, said standard being also provided with a longitudinal series of apertures 25. These apertures are designed to receive locking-pins 26 engaging 25 the lower end portion of an extension post 27 supporting a horizontal top bar 28. Arranged upon one end of this top bar is a knob 29 preferably formed of rubber, while extending from the other end of the top bar is a 30 fork 30. This top bar is arranged parallel with the track and can obviously be adjusted to any desired elevation simply by sliding the extension post 27 within the standard 23 and then locking said post by 35 means of the pin 26.

When it is desired to use the apparatus herein described one or more pouches or sacks "B" to be delivered from the car are attached to a ring "C" the diameter of which 40 is equal to or slightly less than the diameter of the tripping plate 14. Said plate 14 is swung away from the arm 1 so as to withdraw the prongs 15 from the openings 16. The ring "C" is then inserted between plate 14 45 and arm 1 and said plate is permitted to re-assume its normal position. The prongs 15 will therefore enter the ring "C" and become reseated in the openings 16. The ring "C" will therefore be supported by the 50 prongs and the straps or rings "C" of the pouches "d" will be disposed under the concave edge of the plate 14. After the ring "C" has been secured to the arm 1 in this manner said arm is swung outwardly from 55 the car door so as to assume a position substantially at right angles to the side of the car. It is then held yieldingly in place by placing the hook 3 in engagement with the eye 2. The pouch or pouches "D" to be delivered to the car are placed upon a ring "E" which is similar to the ring "C". Said ring "E" is then placed in position upon the fork 30 and a portion of the ring will extend downward between and below the fork 30. 60 This downwardly projecting portion has the

pouches "D" suspended from it, and the weight of said pouches will be sufficient to hold the ring "E" in an upright position. When the car reaches the point where the interchange of mail is to be effected the plate 14 is brought forcibly against the knob 29 carried by the top bar 28 of the crane. Obviously this knob cannot contact with plate 14 until it passes into the ring "C". Plate 14 will be pressed backward by the knob 29 70 a sufficient distance to withdraw the prongs 15 from the openings 16. Ring "C" will therefore slide by gravity off of the prongs and will drop on to the top bar 28 which will thus operate to support the ring and the 75 pouches "D" carried thereby. Plate 14 will slide along the bar 28 until after the crane has been passed, whereupon the springs 18 will assist the gravity force in returning the tripping-plate 14 to its normal or vertical position. While the foregoing operation is 80 taking place the finger 21 of arm 20 passes into the upstanding ring "E" and said ring is thus drawn off of the fork 30 and becomes seated upon arm 20 and against the plate 19. 85 It will be seen therefore that the ring will be securely held not only by the inclined arm 20 but also by the upwardly curved end 22 of the finger 21. During the interchange of mail the arm 1 will of course yield backwardly under the impact, this yielding movement being permitted by the elastic brace formed by rod 4 and the tubular member 5 together with the spring connection 8 90 therebetween. Immediately subsequent to this yielding movement the spring 8 will return the arm 1 to its normal position and by unhooking the rod 4 from the arm, said arm 95 can be swung back into the car door. When the apparatus is not in use the rod 4 can be 100 placed in engagement with an eye 31 at one side of the door and will thus act as a guard.

Attention is here called to the fact that suitable slots 43 are formed in the ears 12 for the reception of the free ends of the spring 18 110 when the train is traveling rapidly and the tripping plate is thrown violently upward from normal position by the crane. It will also be noted that a removable pin 44 forms 115 a detachable connection between the arm, and the eyes 45 of the supporting brackets 46 thereby permitting the ready removal of the catcher arm when desired.

It will be seen that the apparatus herein described is very simple and durable in construction and can be readily applied to mail cars without making any changes in the structure thereof. The mechanism is of such a character that it becomes impossible 120 to release the pouches carried by the car unless the ring from which they are supported is so located as to be positively engaged by the crane. This is an important feature because it positively eliminates all danger of the pouches being dropped upon the ground 125 130

and sucked under the car. Obviously the mechanism can be so constructed as to be readily changed to either side of the car door.

What is claimed is:—

5. 1. In apparatus of the character described the combination with a support; of a member movably connected thereto, and supporting devices extending from and movable with said member, said devices projecting 10 into and being removable from the first mentioned support.

2. In apparatus for catching and delivering mail the combination with a supporting arm; of a member movably connected there- 15 to and extending therebelow, and supporting devices extending from said member and normally projecting into openings within the arm.

3. In apparatus of the character described 20 the combination with a supporting arm; of a member movably connected to and extending below said arm, yielding means for holding said member normally in a predetermined relation to the arm, and supporting 25 devices extending from said member and disposed, when said member is in normal position, within openings in the arm.

4. In apparatus of the character described 30 the combination with a supporting arm; of a tripping plate hingedly connected to and extending beyond the arm, means for holding said plate normally in a predetermined relation to the arm, and means extending from the plate and normally seated within open- 35 ings within the arm.

5. In apparatus of the character described 40 the combination with a supporting arm; of a tripping plate hingedly connected to the arm, means for holding the plate normally in a predetermined relation to the arm, and a supporting prong extending from the plate and normally projecting into the arm.

6. In apparatus of the character described 45 the combination with a hingedly supported arm; of a tripping-plate hingedly connected to and extending beyond the arm, said plate having a concave peripheral portion, yielding means for holding the plate normally in a predetermined relation to the arm, and a 50 supporting prong extending from the plate, there being an aperture within the arm and constituting a seat for the prong.

7. In apparatus of the character described the combination with a hingedly supported

arm and a spring-controlled connecting de- 55 vice detachably secured to the arm; of a tripping-plate hingedly connected to and ex- tending beyond the arm, a supporting device extending from said plate and normally en- gaging the arm, and a pouch-engaging ring 60 upon said supporting device and interposed between the arm and plate, said ring ex- tending below the plate.

8. In apparatus of the character described 65 the combination with a support; of a tripping plate hingedly connected to the support, a pouch-engaging ring interposed between the support and the tripping-plate, and means carried by said plate for supporting the ring in position between the plate and support. 70

9. The combination with a crane and 75 means thereon for supporting a ring in a ver- tical position; of a movably supported arm, pouch-supporting means carried thereby and disposed to be released by contact with the crane, and means extending from the arm for engaging a ring supported by the crane.

10. The combination with a crane includ- 80 ing a top bar, a knob at one end of the bar, and means at the other end of the bar for supporting a pouch carrying ring in an up- right position; of a movably supported arm, pouch-carrying means thereon and disposed to be contacted and released by the knob, and means upon the arm for engaging a ring 85 supported by the crane.

11. The combination with an arm, a tri- 90 pping-plate hingedly connected thereto, a ring interposed between the plate and arm, and means carried by the plate for supporting the ring; of a crane, and means upon the crane for projecting into the ring to release the ring, said released ring being disposed to drop said means.

12. In apparatus of the character described 95 a crane comprising a tubular standard, a post adjustably mounted therein and ex- tending thereabove, means for securing the post in adjusted position, a top bar upon the post, a knob at one end of said bar, and a 100 fork at the other end of the bar.

In testimony that I claim the foregoing as my own, I have hereto affixed my signature in the presence of two witnesses.

CHARLES E. HARRELL.
